US00D578129S

(12) **United States Design Patent**
Weber

(10) **Patent No.:** **US D578,129 S**
(45) **Date of Patent:** **** Oct. 7, 2008**

(54) **NOTEBOOK COMPUTER SLEEVE**

(75) Inventor: **Michael Weber**, Litchfield, IL (US)

(73) Assignee: **Atypykal, Inc.**, Litchfield, IL (US)

(**) Term: **14 Years**

(21) Appl. No.: **29/291,651**

(22) Filed: **Sep. 7, 2007**

(51) **LOC (8) Cl.** **14-02**

(52) **U.S. Cl.** **D14/440**

CLAIM

The ornamental design for a notebook computer sleeve, as shown.

DESCRIPTION

FIG. 1 is a first perspective view of a first embodiment of the notebook computer sleeve of my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a second perspective view thereof;

FIG. 9 is a first perspective view of a second embodiment of the notebook computer sleeve of my new design;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom plan view thereof; and,

FIG. 16 is a second perspective view thereof.
